CLAIM

The ornamental design for a hair retainer head wear, substantially as shown and described.

DESCRIPTION

FIG. 1 is a side elevational view of a hair retainer head wear showing my new design;

FIG. 2 is a front elevational view thereof;

FIG. 3 is a rear elevational view thereof;

FIG. 4 is a bottom plan view thereof;

FIG. 5 is a top plan view thereof; and

FIG. 6 is a perspective view in worn position; the broken lines shown are for illustrative purposes only.
